United States Patent Office

Des. 232,050
Patented July 9, 1974

232,050

LIGHT FIXTURE

Fred M. Gore, Dallas, and Ralph H. McFarlin, Pasadena,
Tex., assignors to Esquire, Inc., New York, N.Y.

Filed Apr. 11, 1973, Ser. No. 350,154

Term of patent 14 years

Int. Cl. D26—03

U.S. Cl. D48—31

FIG. 1 is a side view of one embodiment of a light fixture embodying our design;

FIG. 2 is a top view of such one embodiment;

FIG. 3 is a bottom view of such one embodiment; and

FIG. 4 is a side view of another embodiment of a light fixture embodying our design.

The flat surface on the bottom of each light fixture is a window.

We claim:

The ornamental design for a light fixture, substantially as shown and described.
